P. GROEBER.

WALL AND CEILING COVERING.

No.19,611.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,611, dated January 28, 1890.

Application filed December 28, 1889. Serial No. 335,071. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design is in the German renaissance style, consisting of a man's face 1, from which branch two scrolls 2 and 3, each leading to a griffin's head 4 and 5. From either side of figure 1 branch sheaths 6 and 7, and above the face are two expanded flowers 8 and 9.

15 In center of design is a bouquet 10.

On top of design are two scrolls 11 and 12, and the design is generally filled in with an ornamentation of fruits 13 and flowers 14 and 20 floral scrolls. At the extreme edge of design, right and left, are shown animals' heads 15 and 16.

What I claim is—

The design for a wall and ceiling covering 25 herein shown and described, consisting of a man's face, from which branch scrolls leading to a griffin's head, with scrolls, flowers, and other ornamentations.

PAUL GROEBER.
